2-CARBETHOXAMINOBENZAMIDES

Shreekrishna Mammoohan Gadekar, Valley Cottage, N.Y.,
assignor to American Cyanamid Company, Stamford,
Conn., a corporation of Maine
No Drawing. Filed Nov. 7, 1963, Ser. No. 322,973
6 Claims. (Cl. 250—295)

This invention relates to new organic compounds and more particularly is concerned with novel 2-carbethoxyaminobenzamides of the formula:

wherein R₁ is a member of the group consisting of lower alkyl, lower dialkylamino lower alkyl, pyridyl lower alkyl, hydroxy lower alkyl, pyridyl and allyl, X is hydrogen or halogen, and the non-toxic acid addition salts thereof. Suitable lower alkyl substituents contemplated by the present invention are those having from 1 to 6 carbon atoms such as methyl, ethyl, n-propyl, isopropyl, etc. Halogen is exemplified by chlorine.

The compounds of this invention are, in general, crystalline solids ranging in color from colorless to yellow. The non-basic members (i. e., those in which R₁ is lower alkyl, hydroxy lower alkyl, or allyl) are soluble in lower alkanols, sparingly soluble in water, and relatively insoluble in ether, petroleum ethers, benzene, toluene, and the like. The basic members (i.e., those in which R₁ is lower dialkylamino lower alkyl, pyridyl lower alkyl or pyridyl) are sparingly soluble or relatively insoluble in water, but soluble in most organic solvents such as lower alkanols, acetone, chloroform, benzene, toluene, and the like. The latter, basic compounds, form acid addition salts, and these salts are soluble in water and methanol, but are not soluble in non-polar organic solvents such as ether, petroleum ethers, benzene, and the like.

The compounds of this invention are central nervous system depressants. In particular, they show depressant action of the tranquilizer-muscle relaxant type, and show good activity at non-toxic doses.

This activity is demonstrated in several ways. A useful tranquilizer test consists in measuring the reduction of spontaneous motor activity in animals. For example, the compounds of this invention are administered intraperitoneally at graded dose levels to groups of five mice. At the time of peak effect, each group of mice is placed in an actophotometer (photoelectric device for quantitatively measuring locomotor activity) for a period of five minutes. Parallel control groups of five mice are given starch vehicle and their activity is also determined in a similar fashion. The average motor activity of the treated and control groups is compared and the percent reduction of motor activity due to the active agent is calculated. If desired, the dose which produces a 50% reduction in motor activity may also be calculated from the results of several different dose levels. The use of reduced motor activity as a measure of tranquilizing activity has been described by W. D. Gray, A. C. Osterberg and C. E. Rauh, Archives Internationales de Pharmacodynamie et de Therapie, vol. 134, page 198 (1961), and by W. K. Kinnard and C. J. Carr, Journal of Pharmacology and Experimental Therapeutics, vol. 121, page 354 (1957).

A test which is designed to demonstrate muscle relaxant properties consists in measuring the ability of animals to remain on an inclined screen. Groups of ten mice or rats are given intraperitoneal doses of the new compound

2

at three or more graded dose levels. The animals are placed on a $\frac{1}{4}$ inch wire mesh screen inclined at a 60° angle immediately after receiving the compound. This is a modification of the method reported by M. G. Allmark and W. M. Bachinski, Journal of the American Pharmaceutical Association, vol. 38, page 43 (1949). The animals are observed for 20 minutes or longer and the proportions of animals falling off the screen at each dose level are recorded. The dose which produces this effect in 50% of the animals is calculated (IS_{50}). The use of an inclined screen test as a measure of muscle relaxant activity has been described by L. O. Randall, Diseases of the Nervous System, vol. 21 (March Supplement), page 7 (1960). When the new compounds of this invention are tested in mice as described above, they show good muscle relaxant activity at non-toxic doses.

The compounds of this invention may be used in the form of their free bases or as the non-toxic acid addition salts such as the hydrochloride, sulfate, phosphate, etc. The compounds may be administered orally or parenterally and when so administered are active central nervous system depressants at individual doses ranging from about 200 to 1000 milligrams. The dosage regimen can be adjusted to provide the optimum therapeutic response. For example, several doses may be administered daily, or the dose may be proportionately reduced as indicated by the exigencies of the therapeutic situation.

For therapeutic administration the new compounds may be incorporated with pharmaceutical excipients and used, for instance, in the form of tablets, dragees, capsules, suppositories, liquids to be administered in drops, emulsions, suspensions, syrups, chocolate, candy, chewing gum, and the like. Such compositions and preparations should contain at least 0.1% of the active ingredient. The percentage in the compositions and preparations may, of course, be varied and may conveniently be between 2% and about 60% or more of the weight of the unit. The amount of active ingredient in such therapeutically useful compositions or preparations is such that a suitable dosage will be obtained. Preferred compositions or preparations according to the present invention are prepared in such a manner that an oral dosage unit form contains between about 200 milligrams and about 1000 milligrams of the novel compound.

Tablets, pills, dragees, and the like may contain the following: a binder such as gum tragacanth, acacia, corn starch or gelatin; a disintegrating agent such as corn starch, potato starch, alginic acid, or the like; a lubricant such as stearic acid, magnesium stearate, talc, or the like; and a sweetening agent such as sucrose or saccharin may be added, as well as flavoring such as peppermint, oil of wintergreen, or cherry flavoring.

The compounds of this invention may be prepared by reacting an appropriately substituted antranilamide with ethyl chlorocarbonate according to the following general reaction scheme:

wherein R₁ and X are as hereinabove defined.

Ordinarily the reaction is carried out without a solvent, an excess of the ethyl chlorocarbonate serving as a solvent. If desirable, however, an inert solvent may

be used such as toluene, xylene, or the like. The reaction mixture is heated to refluxing temperature, which is, generally, a temperature ranging from about 75° C. to about 130° C., and maintained at such temperature for a period of time ranging from about one-half hour to about 5 hours, after which time the reaction is complete, or substantially complete. On cooling the reaction mixture, the product often precipitates out. Otherwise, conventional methods of evaporation and concentration may be required to effect isolation of the crude product. The crude product may then be purified by standard procedures, ordinarily recrystallization from a solvent such as lower alkanol.

The invention will be described in greater detail in conjunction with the following specific examples.

EXAMPLE 1

Preparation of *N*-(2-dimethylamino)ethyl-2-carbethoxyaminobenzamide hydrochlorideA solution of 10.4 g. (0.0500 mole) of *N*-(2-dimethylamino)ethyl anthranilamide and 125 ml. of ethyl chlorocarbonate was heated over steam for three hours. The mixture was evaporated down to dryness in vacuo, and the resulting tan product, melting point 152–157 dec., was washed with ether and collected by filtration; yield 12.8 g., 81%. On recrystallization of 3.15 g. from ethanol, ethanolic hydrochloric acid and ether (decolorizing charcoal) a 63% recovery, melting point 159–160.5, was obtained.

EXAMPLE 2

Preparation of *N*-(3-dimethylamino)propyl-2-carbethoxyaminobenzamide hydrochlorideA mixture of 11.1 g. (0.0500 mole) of *N*-(3-dimethylamino)propyl anthranilamide and 125 ml. of ethyl chlorocarbonate was refluxed for three hours. The mixture was cooled and the cream-color product was filtered and thoroughly washed with ether; yield, 15.8 g., 96%; melting point 178–180 eff. One recrystallization of 3.0 g. from ethanol, ethanolic hydrochloric acid and ether (decolorizing charcoal) gave the analytical sample in 78% recovery, melting point 182.5–184 eff.

EXAMPLE 3

Preparation of *N*-(3-dimethylamino)propyl-2-carbethoxyamino-5-chlorobenzamide hydrochloride5

solid was filtered and then triturate with cold ethanol and dried, weight 3.0 g. (82%), melting point 213-214°. A sample recrystallized from methanol and ether melted at 222-223°.

EXAMPLE 7

Preparation of *N*-(2-hydroxy)ethyl-2-carbethoxyaminobenzamideA mixture of 2.70 g. (0.0150 mole) of *N*-(2-hydroxy)ethyl anthranilamide and 35 ml. of ethyl chlorocarbonate was heated over steam for three hours. The residue which remained when the solution was evaporated down to dryness was treated with 50 ml. of ether. This mixture was filtered, and the filtrate was allowed to stand at room temperature overnight. The white product which remained when the ether evaporated off was triturated with a minimum of ether and collected by filtration, 1.58 g. (42%). One recrystallization from benzene and petroleum ether (decolorizing charcoal) gave the analytical sample, melting point 104-107°.

EXAMPLE 8

Preparation of *N*-ethyl-2-carbethoxyaminobenzamideA mixture of *N*-ethyl anthranilamide (1.31 g., 0.00800 mole) and ethyl chlorocarbonate (24 ml.) was refluxed over steam for 2½ hours. The excess ethyl chlorocarbonate was evaporated off, and the resulting residue was recrystallized from petroleum ether to give 1.31 g. (69%) of the product, melting point 100-101°.

EXAMPLE 9

Preparation of *N*-(2-hydroxy)ethyl-2-carbethoxyamino-5-chlorobenzamideA mixture of 6.44 g. (0.0300 mole) of *N*-(2-hydroxy)ethyl-5-chloro anthranilamide and 70 ml. of ethyl chlorocarbonate was refluxed over steam for three hours. The orange solution was evaporated down to dryness in vacuo, and the resulting oil was dissolved in ~40 ml. of ether.

The ethereal solution was filtered, and the filtrate was allowed to stand at room temperature overnight. The tan crystalline product was collected by filtration; yield 4.57 g., 54%. One recrystallization from benzene (decolorizing charcoal) gave the analytical sample, melting point 101-103° clear.

EXAMPLE 10

Preparation of *N*-(*t*-butyl)-2-carbethoxyaminobenzamide*N*-(*t*-butyl) anthranilamide (5.77 g., 0.0300 mole) and 90 ml. of ethyl chlorocarbonate were heated on a steam bath for three hours. The brown solution was evaporated down to dryness in vacuo, and the residue was treated with ~125 ml. of ether. The granular product, 4.80 g., was filtered off, washed with ether. When the combined filtrate was washed were concentrated to ~50 ml. and petroleum ether was added until cloudy, and additional 2.52 g. of product was obtained (total yield 92%). A sample recrystallized from benzene and petroleum ether (decolorizing charcoal) gave analytically pure product, melting point 161-163°.

EXAMPLE 11

Preparation of 2-carbethoxyamino-*N*-(2-pyridyl)benzamide hydrochlorideA mixture containing 5.3 g. of the anthranilamide and 62 ml. of ethyl chlorocarbonate was refluxed for three hours. The mixture was cooled and the solid was filtered and air dried; weight 5.0 g. (62%), melting point 172-175°.

A sample of the free base was prepared in the following manner: a 0.2 g. sample of the hydrochloride was dissolved in 5 ml. of water. The aqueous solution was rendered alkaline by an addition of 5% aqueous solution of sodium bicarbonate when the base precipitated. This was filtered, dried and then recrystallized from aqueous ethanol; recovery (60%); melting point 132-133°.

EXAMPLE 12

Preparation of *O*-amino-*N*-(3-picoly)benzamideTo a 40 ml. of aqueous solution containing 8.6 g. (0.08 mole) of 3-picolyamine was added 3.3 g. (0.02 mole) of isatoic anhydride. The reaction mixture was allowed to stand at room temperature overnight. The resultant brown solution was diluted with 5 ml. of water and cooled in ice-water bath whereupon 3.2 g. (70%) of a white product was obtained. A single recrystallization from aqueous ethanol gave a crystalline solid melting at 125-126°.

EXAMPLE 13

Preparation of 2-amino-5-chloro-*N*-(3-picoly)benzamideTo a 20 ml. of aqueous solution containing 4.3 g. (0.04 mole) of 3-picolyamine was added 1.98 g. (0.01 mole) of 5-chloroisatoic anhydride. The mixture was allowed to stand at room temperature overnight and the precipitated solid was filtered and washed with water; weight 1.8 g. (69%). A sample recrystallized from ethanol and water melted at 141-142°.

EXAMPLE 14

Preparation of *N*-allyl-2-amino-5-chloro benzamideTo a solution of 1.5 g. (0.025 mole plus 3% excess) of allylamine in 10 ml. of water was added in small portions 4.85 g. (0.025 mole) of 5-chloroisatoic anhydride at room temperature. The precipitated product was recrystallized from 50% aqueous ethanol to give 2.0 g. (40%) of light tan platelets, melting point 123.5-124.5°.

EXAMPLE 15

Preparation of 2-amino-5-chloro-N-2-hydroxyethyl benzamide

To 6 ml. (0.1 mole) of ethanolamine was added 19.8 g. (0.1 mole) of 5-chloroisatoic anhydride. The mixture was stirred and 25 ml. of water was added and then was heated over steam for two hours. The warm mixture was diluted with 150 ml. of cold water and cooled whereupon 12.2 g. (57%) of a solid was obtained. A sample recrystallized from benzene melted at 126-129°.

EXAMPLE 16

Preparation of 2-amino-N-(3-dimethylamino) propyl benzamide

To a 250 ml. of aqueous solution containing 56.1 g. (0.5 mole) of 3-dimethylaminopropylamine was added 16.3 g. (0.1 mole) of isatoic anhydride. The mixture was stirred for six hours and then was left at room temperature for 48 hours. The resultant brown solution was diluted with 500 ml. of water and was extracted thoroughly with ether. Evaporation of ether extracts gave an oil. The oil was dissolved in a mixture of 20 ml. of heptane and 30 ml. of ethanol and then treated

with 25 ml. of alcoholic hydrochloric acid. The precipitated hydrochloride was recrystallized from a mixture of methanol and ethanol; yield 67%; melting point 219-221°.

EXAMPLE 17

Preparation of 2-amino-N-(dimethylamino) ethyl benzamide

To a 50 ml. of aqueous solution containing 8.82 g. (0.1 mole) of beta-dimethylaminoethylamine was added 8.16 g. (0.05 mole) of isatoic anhydride. The mixture was stirred for six hours and was then allowed to stand at room temperature overnight. The mixture was diluted with 100 ml. of water and then was rendered strongly alkaline by addition of 5 N sodium hydroxide. It was then extracted thoroughly with ether. Evaporation of ether layer gave an orange oil. The oil was redissolved in ether, dried over magnesium sulfate and was then converted to the hydrochloride by an addition of alcoholic hydrochloric acid; yield (82%). A sample recrystallized from a mixture of methanol and ethanol melted at 139-141°.

EXAMPLE 18

Preparation of pharmaceutical tablets

40 The active ingredient is incorporated into a standard pharmaceutical tablet according to the following formulation:

	Per Tablet	For 10,000 Tablets
45		
Active Ingredient.....	Grams	Grams
Corn starch (for mix).....	0.200	2,000
Corn starch (for paste).....	0.015	150
Alginic acid.....	0.015	150
50 Methocel (400 centipoises).....	0.020	200
	0.005	50
Magnesium stearate (1%).....	0.255	2,550
	0.003	30
	0.258	2,580

55 The active ingredient, corn starch (for mix), alginic acid, and Methocel are blended together. The corn starch (for paste) is suspended in 600 milliliters of water and heated, with stirring to form a paste. This paste is then used to granulate the mixed powders. Additional water is used, if necessary. The wet granules are passed through a No. 8 hand screen and dried at 120° F. The dry granules are then passed through a No. 16 screen. The mixture is lubricated with 1% magnesium stearate and compressed into tablets in a suitable tableting machine.

I claim:

1. A compound selected from the group consisting of 2-carbethoxymnobenzamides of the formula:

70

75

wherein R₁ is a member selected from the group consisting of a lower alkyl, lower dialkylamino lower alkyl, pyridyl lower alkyl, hydroxy lower alkyl, pyridyl and allyl, X is a member selected from the group consisting of hydrogen and halogen, and the non-toxic acid addition salts thereof.

2. N-(2-hydroxy)ethyl-2-carbethoxyaminobenzamide.
3. 2-carbethoxyamino-N-(3-picolyl)benzamide.
4. N-(2 - dimethylamino)ethyl - 2 - carbethoxyamino-
benzamide hydrochloride.
5. N-ethyl-2-carbethoxyaminobenzamide.
6. N-allyl-2-carbethoxyamino-5-chlorobenzamide.
